US00D700967S

(12) **United States Design Patent**
O'Leary et al.

(10) **Patent No.:** US D700,967 S
(45) **Date of Patent:** ** Mar. 11, 2014

(54) **HANDLE FOR PORTABLE SURGICAL DEVICE**

(75) Inventors: **Jeremiah O'Leary**, Chicago, IL (US);
Derek Dee Deville, Miami, FL (US);
Kevin W. Smith, Coral Gables, FL (US);
Matthew A. Palmer, Miami, FL (US);
Luke Waaler, Longmont, CO (US)

(73) Assignee: **Covidien AG** (CH)

(**) Term: **14 Years**

(21) Appl. No.: **29/404,130**

(22) Filed: **Oct. 17, 2011**
(Under 37 CFR 1.47)

Related U.S. Application Data

(62) Division of application No. 13/215,971, filed on Aug. 23, 2011.

(57) **CLAIM**

The ornamental design for a handle for portable surgical device, as shown and described.

DESCRIPTION

FIG. 1 is an elevational view of a right side of a handle for portable surgical device in accordance with the present design;

FIG. 2 is an elevational view of a left side of the handle for portable surgical device of FIG. 1;

FIG. 3 is an elevational view of a rear side of the handle for portable surgical device of FIG. 1;

FIG. 4 is an elevational view of a front side of the handle for portable surgical device of FIG. 1;

FIG. 5 is an elevational top plan view of the handle for portable surgical device of FIG. 1;

FIG. 6 is an elevational bottom plan view of the handle for portable surgical device of FIG. 1;

FIG. 7 is a perspective view of the left side of the handle for portable surgical device of FIG. 1 from above the front thereof;

FIG. 8 is a perspective view of the right side of the handle for portable surgical device of FIG. 1 from below the rear thereof; and,

FIG. 9 is a perspective view of the right side of the handle for portable surgical device of FIG. 1 from above the rear thereof. The broken line showing is for environmental purposes only and forms no part of the claimed design.
